UNITED STATES PATENT OFFICE.

EDWARD E. CLEMENT, OF WASHINGTON, DISTRICT OF COLUMBIA, ASSIGNEE, BY
MESNE ASSIGNMENTS, TO FREDERICK C. STEVENS, OF ATTICA, NEW YORK.

TELEPHONE-EXCHANGE SYSTEM.

1,107,146.

Specification of Letters Patent. Patented Aug. 11, 1914.

Application filed July 14, 1906. Serial No. 326,251.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems and has for its object the improvement and simplification of such systems, and particularly the provision of connective means for exchange purposes 15 which shall comprise as its essential elements relays only. This arrangement is particularly useful in automatic and semi-automatic systems, but is applicable to many other types both for exchange and substanc- 20 tion or intercommunicating systems.

The arrangement which I shall herein- after specifically describe, while somewhat limited in its scope as to the number of lines, is intended to be typical only, and to 25 serve the purpose of demonstrating the principles which I intend to apply in systems of all sizes and many kinds.

I attain my object by providing a plurality of relays controllable by means of circuit closers which in a semi-automatic system such as hereinafter described, are actuated by an operator at the central office; and in a full automatic system are actuated by 30 means of switching devices controlled in the ordinary manner by means of predetermined numbers of impulses sent from a subscriber's station.

In the preferred form of its present embodiment, my invention contemplates a decimal arrangement of relays with a plurality of circuit closers corresponding to the decimal digits. This will be best understood by giving an example. Suppose we have 100 subscribers' lines to be interconnected, then 40 the operator is given 20 circuit closers, 10 of which control the circuits of what I call the "tens" relays, and the others control the circuits of the "units" relays. Each tens relay closes 10 circuits, and each units relay 45 closes a single circuit which is multiplied to corresponding contacts in all 10 of the tens relays. When the line calls, it becomes connected temporarily with an idle trunk, this trunk terminating in a set of relays such as 50 55 I have referred to. Ascertaining, we will

assume, that the number wanted is 94, the operator depresses the number 9 button of the circuit closers in the tens group and the number 4 button in the units group. The effect of this is to close the circuit of the 9th tens relay associated with the trunk, and the 4th units relay, thereby continuing the trunk connection through the respective contacts of these relays to line number 94.

Where the number of lines exceeds 100, the operator has correspondingly increased sets of buttons, one set of 10 buttons being added for each decimal digit added to the size of the exchange. For a 10,000 line exchange the operator would have four sets of buttons, for 1,000 lines she would have three, for 100 lines two, and for 10 lines one. For a 1,000 line equipment, double sets of trunks, that is selectors and line connectors, are required. The incoming calls land on what I may call incoming trunks, which terminate in selector sets of relays, each set in this case consisting of only 10 relays since we have only to connect the trunk to any one of 10 groups of hundreds trunks to the connectors. The secondary trunks run to the connectors which consist of the full equipment of tens and units relays as heretofore specified. The wires from the operator's first set of buttons run to the selector set of relays, while the wires from the other two sets run to the connector sets direct.

It will be understood that there are a number of trunks in an exchange of any size and there may also be a plurality of operators, hence it is not advisable to leave the operators' controlling circuits permanently connected to the relays of any particular trunk. When a trunk gets into service, therefore, I provide a controlling relay which immediately connects the appropriate controlling wires from an idle operator to the selecting or connecting relays as the case may be.

Where a larger number of lines is to be served, as in exchanges of over 1,000 subscribers, I find it not entirely practical to have direct controlling wires passing from the operators' keys to the trunk relays. I therefore use a combination of automatic switches and relays, which I consider to be broadly novel and original with myself.

In a preferred modification the incoming lines are multiplied to primary selector relay sets such as will be hereinafter described,

and these relay sets are controlled by a constantly acting primary selector switch consisting of a spindle rotating so as to sweep its arms around a circular system of line contacts which may be composed of 100 for each switch. When a line is calling and its circuit is therefore closed at the substation, the revolving switch picks it up and at the instant of touching this contact connects 5 battery to the relay, which becoming energized, pulls up and supplies battery current to another pair of arms on the shaft which at the instant are in contact with terminals corresponding to the line calling and connected respectively to the proper tens and 10 units relay to connect the calling line on to an incoming trunk. Of these relay terminals, the tens terminals would be broad faced so that contacts would persist with each one 15 of them while corresponding contact is made with ten of the units terminals. On the other hand, the different units terminals all round the circle are multiplied together, all the number ones being joined, all the number twos, etc. An incoming line having thus 20 been landed on the trunk, immediately derives current from the trunk through the sleeve relay thereof in the usual manner, so that the cut-off relay of the line holds it 25 disconnected from the primary selector switch. The operator is preferably provided with a selector switch having a starting circuit and a starting relay, so that when the aforementioned call lands on the trunk 30 and its sleeve relay pulls up, the said relay closes battery current on to the operator's starting circuit (which may be common to the switches to all the operators) whereupon the operator's switches start to find and 35 connect with the calling trunk. The first idle switch picks up the trunk and the operator is then able to communicate with the calling subscriber and ascertain the number wanted. The trunk has associated with it a ten-point 40 switch, driven by a step by step magnet, and when the operator punches the first button in her set she sends a corresponding number of impulses to this switch which thereupon steps around to select the first digit of the 45 number wanted which we will assume to be 9 in the number 9999. The 9th contact in this switch is connected to a terminal in a hundred-point switch constantly driven and similar in every respect to the primary selector switch I have before mentioned, there 50 being ten of these switches, each controlling a group of trunks. This ninth switch is associated with the ninth group of thousands trunks, and when its selecting arm comes 55 around to the contact associated with the incoming or calling trunk it takes current from the contact through a relay associated with the switch which closes and puts current onto two arms which at the instant rest 60 on two contacts which are in connection with 65

the relay terminals. These two contacts are connected respectively to tens and units relays which pick up the calling trunk, and put it on through their contacts to their trunks of the nine thousand group, which 70 happens to be the first idle trunk of that group. The next set of nine impulses comes through this nine thousand group and in the same manner work a ten point selector switch to select the hundreds group wanted 75 which is likewise, number nine. Each hundreds group also has its back testing selector switch and when the ninth switch comes around to the contact which has been made busy it pulls up its relay, and puts current 80 on the ten and units relay of the first idle trunk of its group which will connect that trunk back to the calling trunk. Associated with this last or hundreds group to which we have now penetrated is a group of tens 85 relays and ten units relays, together with two ten point switches one for each of these sets of relays. These two switches are worked, the first to pick out the number ninety relay and energize it and the second 90 to pick out the number nine units relay and energize it. The combined effect of these two relays is to connect line number ninety-nine to their trunk number nine hundred. As we already have the nine thousands trunk 95 connected onto this, and as the calling line also is connected onto that, we thus have a complete calling circuit from the connecting line through to line number nine thousand 100 nine hundred and ninety-nine.

In the small exchange which is specifically illustrated and described herein I provide each line with an individual relay which when the line is calling closes the circuit of the tens and units relays to connect it to an 105 idle trunk without the intermediation of the rotating switch to which I have referred. Also, instead of finding any switches necessary to pick out the relays in making selection of the line wanted, I am enabled to 110 carry the individual wires from these relays back to the operator, who has simple circuit closers whereby she can select and energize any one or two or more of the relays as she may desire.

It will be understood that I have shown only essentials in the diagram herewith, and I do not limit myself to any particular means of testing, of ringing, or the like. The essential feature of my invention, and the characteristic arrangement which it is my intention to cover broadly is the relay control and the completion of talking circuits entirely through relays in the interconnection of lines.

My invention is illustrated in the accompanying drawings wherein—

Figure 1 shows three subscribers' stations and lines. Figs. 2, 3 and 4 show portions of three primary selector sets. Fig. 5 shows a 130

talking trunk with a secondary set and selective keys. Fig. 5^a is a view showing the distribution of calls among the various trunks. Fig. 6 shows a set of connector relays. Fig. 7 is a condensed diagram of a primary selector set. Fig. 8 is a modification showing how a mechanical switch can be substituted for the relay primary selector set. Figs. 9 and 10 are respectively a side and top plan view of a ten point relay used in my system. Fig. 11 is a diagram supplemental to Fig. 5, showing the lock-out arrangement for the ringing relay. Figs. 12 to 15 inclusive, when put together, present the whole of a diagram showing the application of a positively acting driven primary selector switch to the primary selector relay sets.

Before proceeding to the circuits, where 20 in the invention in the present case resides, it will be advisable to obtain a clear understanding of the types of apparatus which I employ, and which are shown in Figs. 9 and 10, inclusive. I do not give any special illustration of a single point or ordinary relay, 25 for the reason that everyone skilled in the art is so familiar with these devices as to render it unnecessary. That portion of my system which is illustrated in Figs. 2, 3 and 30 4 constitutes what I have termed the primary selector or answering portion of the system. In this, as already set forth, appear a number of ten point relays and a number of single point or ordinary relays. These 35 latter may be of any suitable type. The only special feature required is that of double winding, which, as I shall point out herein-after, can be dispensed with if some other means be provided for locking the relays 40 when energized. The apparatus at the subscribers' stations also forms no part in itself of my present invention, except as it co-acts with the apparatus and circuits at the central office. I contemplate using an ordinary 45 common battery telephone outfit the same as those employed in standard manual switch-board systems. Referring then to Figs. 9 and 10, I will briefly describe the ten point relay, N. This comprises an iron back yoke, 50 n, a pair of magnets n', mounted thereon, an armature n², extending across the front end thereof, and a set of contact-springs, n³, n⁴, n⁵, n⁶, overlying the upper bell-crank extension of the armature, so as to be worked 55 thereby. There are eleven sets of these springs, all secured at the rear end of the relay upon the return member, n⁷, of the back yoke. The front ends or pole pieces of the cores of the electro-magnets, n', receive 60 the front yoke, n⁸, of non-magnetic material, such as brass, this also having an upper return portion, n⁹, overlying the magnet windings, alined with the return portion, n⁷, of the back yoke, n. Upon this return portion, 65 n⁹, of the front yoke the upper bell-crank

arm, n¹², of the armature, n², lies flat under normal conditions. Cut from end to end of this upper bell-crank portion, n¹², are two grooves in which rest the insulating studs of the spring sets. The function of these 70 slots with the studs resting in them is to retain the armature in place. At their front ends the springs are separated by shouldered studs the lowermost stud of each pair resting upon the armature, carrying the lower 75 spring of its pair, n⁶, on its shoulder, and the upper spring, n⁵, on its head, its stem passing through a hole in the spring, n⁵, while the uppermost stud of each pair rests upon the spring, n⁶, supports the spring, n⁴, 80 upon its shoulder, and carries the spring, n³, on its head, its stem passing through a hole in the spring, n⁴. The actuating studs affect only the springs, n⁴, n⁶, of each set, these constituting the movable springs, while the others, n³, n⁵, are fixed. Each actuating stud 85 carries the spring, n⁶, on its shoulder, and the spring, n⁴, on its head, its stem passing through holes in the springs, n⁵, n⁶.

The entire relay is secured to an insulating 90 back block, n¹⁰, by means of the bolts, n¹¹, constituting extensions of the cores and threaded to receive lock-nuts. The rear ends of the contact-springs extend out through openings made in this block, and 95 an inclosing shell or casing, n¹³, is fitted to the block, with which it forms a tight joint all around the edge. This shell is secured in place by means of the stud, n¹⁴, threaded to receive the nuts, n¹⁵. As the armature, n², is 100 attracted, the springs, n⁴, n⁶, are lifted by the actuating stud, until their outer points make contact with the corresponding points of the springs, n³, n⁵, in each set. Ten of 105 these sets are line-contacts, and the eleventh is for locking purposes, as will sufficiently appear from the description of the circuits.

Having thus described the mechanical parts a knowledge of which is essential to the comprehension of my circuits, I turn to 110 the description of the latter, beginning with Fig. 1. Therein I have shown three subscribers' stations, A, A', A², each equipped with a telephone transmitter, a receiver, a switch-hook, a ringer, and condenser, all of 115 usual or suitable type for use with common battery circuits. When the hook is up, that is when it is relieved of the weight of the receiver, the circuit is through the transmitter and receiver; and when the hook is down, 120 the line-circuit is completed for alternating current only, through the ringer and condenser.

Since the circuits are the same for all the lines, I will refer to the line from station A 125 only. This consists of conductors 1 and 2, extending from the sub-station to the central office. At the substation the talking circuit is completed through the wires 3-4 when the hook is up, and the ringing circuit 130

through the wires 5-6 when the hook is down. These figures are useful for the purpose of tracing the circuits only.

- Turning now to Fig. 2, the line wires 1 and 2 appear at the left hand side of the figure, terminating in contacts of the cut-off relays M' , which are normally deenergized, so that in each case the line-wire 2 is grounded at 7 and the line-wire 1 extended 10 through line 8 to the line-relay M , and so to main battery B and ground. The armature, m , of each line relay M is connected to battery at 9, and when attracted is adapted to close upon terminal contacts of wires leading 15 to the tens and units relays of the primary selector sets. I preferably divide all the incoming lines in an exchange into groups of say one hundred each, and to each group I apportion a fixed number of trunks 20 leading to connective apparatus. In a small or comparatively inactive exchange the percentage of these trunks may be as low as five, and in busy exchanges it may be raised to ten or even fifteen. I assume, however, 25 that ten per cent. of connective apparatus will be sufficient to care for the present system, hence I provide ten trunks for each one hundred lines and a complete set of tens and units relays in a primary selector 30 group for each trunk. The circuits herein illustrated show six lines, which for convenience I will call Nos. 500, 501 and 502 (Fig. 2) and 510, 511 and 512 (Fig. 3). The subscribers' circuits of Fig. 1 will fit any of 35 these, and in order to fully comprehend the connections of these lines and the arrangement of the tens and units relays, it is necessary to consider Figs. 2, 3 and 4 together. In Figs. 2 and 3 the subscribers' extension 40 lines are shown coming into their initial terminals on the tens relays, which are of the type shown in Figs. 9 and 10. Each of these relays carries the terminals of the ten lines, and for each trunk there are ten 45 of these relays, so that for 100 lines, provided with ten trunks, there will be 100 ten point relays, containing 1,000 line-terminals; from which it appears that each line can be multiplied ten times, which it should 50 be in order to obtain access on occasion to every one of the ten trunks. The contacts on the ten point relays are arranged in duplicate pairs. That is, the incoming lines terminate each on one pair of springs, opposite which another pair of springs appears 55 to which the line is connected when the relay is energized, and from which a local circuit passes to the front contact springs of a particular units relay or single point relay. 60 For each group of ten tens relays there are ten units relays, or twenty relays in all for each trunk. A group of this kind constituting one primary selector or dummy trunk terminal for thirty lines, is shown in Fig. 7, 65 apart from the other figures, so as to free the

lines from their multiple connections. In order to make clear the connection of a line coming into the exchange, I will first refer to this figure and then trace the circuits through the others.

In Fig. 7, N , N' , N^2 , are three relays of the type shown in Figs. 9 and 10, having ten pairs of contacts each for the line circuits. These relays correspond to the relays shown in Figs. 2 and 3, correspondingly lettered. 70 At the top of the figure I have shown the terminal ends of lines 500 to 529, inclusive, connected to a pair of contacts, n^3 , n^5 , such as shown in the mechanical Figs. 9 and 10. For lines 500 to 509 these 80 terminals are in the relay N . For lines 510 to 519 they are in the relay N' . For lines 520 to 529 they are in the relay N^2 . Thus each relay contains line-terminals, n^3 , n^5 , for ten lines. When any one of the lines 85 appropriated to a particular relay is calling, the electromagnet, n' , of that relay becomes energized. This will be explained in connection with the circuits of Figs. 1 and 2 farther on. For example, if any line from 90 500 to 509 originates a call, the magnet, n' , of the relay, N , will become energized, and simultaneously connect all of the lines from 500 to 509 onto the extensions 10 to 19, inclusive. If, however, the calling line is in 95 the group from 510 to 519, the magnet, n' , of the relay, N' , will become energized, connecting all that group onto the extensions 10 to 19, inclusive. Similarly, if the calling line be in the third group, from 520 to 529, 100 the magnet, n' , of the relay N^2 will be energized, connecting that entire group onto the extensions 10 to 19, inclusive. Thus extensions 10 to 19 are seen to be common to all of the tens relays, and in fact each extension 105 pair is multiplied to corresponding contacts in all of the tens relays. No. 10 extension goes to the first pair of contacts, n^4 , n^6 , in each of the relays, N , N' , N^2 . Extension No. 11 is multiplied to the second pair of contacts, n^4 , n^6 , in each of the relays, and so on with all the extensions up to No. 19. 110 At the lower edge of Fig. 7, I have shown ten units relays, marked P to P^9 , inclusive. These are the same as the relays in Fig. 4, 115 similarly marked. Each is a simple standard relay, of the type in common use, and preferably of the same general type as that shown in Figs. 9 and 10, hereof, viz., that type in which the electromagnet is mounted 120 horizontally on a frame or rack, carrying the contact springs upon it, and the whole is inclosed within a dust-proof shell. Each relay has an armature, p^2 , adapted to be actuated by an electromagnet, p' , to close 125 together the contacts, p^3 , p^4 , and p^5 , p^6 . In the present instance, that is in the trunk group of each primary selector, all of the contacts, p^5 , of the entire set of relays, P to P^9 , are connected together, forming a set 130

of double parallel branches marked 20 to 29, inclusive, which are really so many bridges across the trunk circuit, 30—31.

The outfit shown in Fig. 7 is sufficient for 5 30 lines, and by its use any one of the lines, 500 to 529, may connect itself to the trunk 30—31, by merely closing its line-circuit, and energizing the appropriate tens and units relays. The energizing circuits are not 10 shown in Fig. 7, but will be described in connection with Figs. 2, 3 and 4. They comprise parallel branches closed by the line-relay of each line when calling, one branch going to the appropriate tens relay, 15 and the other branch going to the appropriate units relay, which thus become energized simultaneously and act in conjunction to connect that particular line and no other to the trunk. For example, suppose line 20 No. 512 is calling, the subscriber having taken down his receiver from the hook, so as to close his line-circuit as shown in Fig. 1, and energize his line-relay, M, shown in Fig. 2. This line-relay closes two branches; 25 one leading to the tens relay, N', in Fig. 7, and the other leading to the units relay, P², which is the third in the set of ten. The actuation of the tens relay, N', connects all of the lines 510 to 519 onto the extensions 10 to 30 30, inclusive; but it will be observed that these extensions are open everywhere else, hence no effect is produced by this action alone. The third units relay, P², however, connects the third extension 12 to the trunk 35 30—31, through the branch 22, and by following the circuits in Fig. 7 it will be found that this connects the line 512 onto the trunk direct, whereupon the trunk relays become energized, and further proceedings may be 40 had. Only one line is thus connected to the trunk at a time, assuming of course that only one tens relay and one units relay of the same set be energized simultaneously. It is true that the tens relay connects all of 45 its lines onto the extensions; but all of these extensions are open except the particular one which is closed onto the trunk by the particular units relay energized. It is also true that the extension thus connected to the 50 trunk is multiplied to the corresponding pair of contacts in every one of the tens relays, but this produces no effect, because all but one of the tens relays remain deenergized.

Before passing from Fig. 7 it is necessary 55 to call attention to the fact that only three tens relays are there shown, accommodating thirty lines. This limitation is due to the necessary limitations of a Patent Office drawing, and it is to be understood that the 60 same principles apply to any desired group up to 100 or more. It is most convenient in a scheme like this to make use of the decimal system, using ten relays per trunk, ten lines per relay, and ten trunk multiples per 65 line. For 100 lines there would be ten of

the tens relays, N, N', N², etc., but still only ten of the units relays, and each of the extensions 10 to 19, inclusive, instead of being multiplied three times, would be multiplied ten times, into all the tens relays. 70

Turning now to Figs. 2, 3 and 4 we have here the same relays described in connection with Fig. 7, but somewhat differently arranged. Only two tens relays and three units relays of each set or of each trunk 75 are shown. I have assumed the members 500, 501 and 502 for the lines entering Fig. 2, and 510, 511 and 512 for the lines entering Fig. 3. The first three lines being within the same tens digits of each other 80 go onto the same tens relays in each set. For the sake of convenience I have given the designating numerals of the relays coefficients. Thus in Fig. 2 all three of the lines come into the relay N, which is adapted to put them onto the extensions, 10, 11, 12, etc., leading to the units relays P, P', P², etc., in Fig. 4. (I should here remark that the tens relays in Figs. 2 and 3 are not shown with their full complements of 90 springs, for the sake of simplicity). Each of the lines 500, 501 and 502 not only terminates in contacts of the relay, N, but is multiplied to similar contacts in the relays 1N, 2N, etc. There would be one of these added for each trunk, that is appropriated to the group of lines. In the present case I only illustrate three trunks, so that each line need be multiplied only three times. 95

In Fig. 3, the lines 510, 511 and 512 are 100 connected to the tens relays, N', 1N' and 2N' in the same manner as the lines in Fig. 2, each line being multiplied three times so that each may have access to any one of the three trunks. It will be understood of course that the relays, N, N', of Figs. 2 and 3, and P, P', P², of Fig. 4, constitute one set, appropriated to the trunk 30—31, and have precisely the same relation among themselves and the same connections, as the set shown in Fig. 7. Similarly the relays 1N, 1N', 1P, 1P', 1P² all belong to one set, appropriated to the trunk-line 130—131. Similarly again, the relays 2N, 2N', 2P, 2P' and 2P² belong to one set, appropriated to 110 the trunk-line 230—231. The extensions from the tens relays to the units are marked 10, 11, 12 for the first set, 110, 111 and 112 for the second set, and 210, 211 and 212 for the third set. As these of course bear a 120 logical relation throughout, and follow the same arrangement as that in Fig. 7, it is thought no difficulty will be experienced in comprehending the meaning of Figs. 2, 3 and 4. If Fig. 7 is understood, the description of the other figures may be put into one sentence. They show several groups like Fig. 7, with the line-wires multiplied to each group instead of terminating as in Fig. 7 in single pairs of contacts. 125 130

The actual connections controlled by the relays N and P being thus understood, it is most important to explain the means by which I control these relays. Referring to Fig. 2, the line-wires 1 and 2 terminate as I have stated, in the contacts of the cut-off relay M', through which they are normally connected to the line relay M and ground. When the subscriber at station A takes the telephone from the hook, he closes his line-circuit, the line-relay M is energized, and the two branch circuits 50 and 51 are immediately closed. The branch 50 passes in multiple to one winding of each of the three tens relays, N, 1N and 2N, these relays being double wound for the purpose of making them self-locking when attracted. Any one of these relays might thus be energized by any one of the three lines shown, but it is my purpose that only one of them shall be so energized at once, and that no two lines shall be able to energize the same relay at the same time. Hence, on the other side of these relays I take away the circuit-wires, which are designated generically by the numerals 54, 55 and 56, to three separate controlling means in the shape of special relays associated with the switch trunks. Each of these first named relays has its locking coil open on one side, but adapted to be grounded by the relay itself in pulling up; and on the other side of this second or locking winding it is connected through one of the wires indicated by 57, 58 or 59, to controlling means similar to those I have just mentioned and which will also be specified later. The second branch from the line relay is marked 51 for line 502; 52 for line 501; and 53 for line 500. In other words, each of these lines has its own units wire, as will be apparent at once if Fig. 7 has been understood. The three wires, 51, 52 and 53, pass along the bottom of Figs. 2 and 3 and into Fig. 4, where they terminate in the first or operating windings of the three relays, P, P' and P'', also by multiples in the corresponding windings of the relays, 1P, 1P', 1P'' and 2P, 2P' and 2P''. The three relays, P, P' and P'', since they belong to the same set, have a common control, their return wires 60^a, 60^b, 60^c, passing to contacts in a twenty-pair relay D''. This relay controls the return wires of both the tens and units relays of this set, twenty in all. I find it advisable to have a relay provided with separate terminal contacts for each of the wires 54^a, 54^b, 60^a, 60^b, etc., of each trunk, because of certain complications which arise when battery is put on without any resistance, the working then being on a margin which is too narrow to be called absolute. In other words, when the controlling relay for any set has cut off the return wires from the actuating windings of the tens and units relays, they are all separated from

each other and as those of one trunk only are closed together at any one time, the separation of the relays associated with the other trunks prevents the formation of any parallel paths when the line calls.

70

Each of the units relays in Fig. 4 has a locking winding separated from the actuating winding and each locking winding terminates on one side in a contact normally open but adapted to be grounded when the relay is energized. All the locking windings of the first set or group have a common return, 61, passing onto the wire 57, which is the control wire of the locking windings on the tens relays, N, N'. This wire 57 passes into Fig. 5 and is there carried to a pair of the trunk relays by which it is controlled.

75

80

The actuating windings of the units relays, 1P, 1P', and 1P'', have return wires 62^a, 62^b, etc., passing to the contacts of the relay D'' associated with trunk 130—131. The locking windings of these relays have a common return 63, which goes to the wire 58, passing into Fig. 5 and there controlled by one of the trunk relays in the same manner as in the first set. Similarly, the actuating and locking windings respectively, of the units relays, 2P, 2P' and 2P'', have their return wires passing into Fig. 5 and there controlled by relays associated with the trunk.

90

It is thought the scheme will now be plain. Suppose that one of the line relays, as that of line No. 502, pulls up. It connects battery to the local circuits 50 and 51 and energizes whichever one of the ten relays, N, 1N or 2N happens to be idle and eligible, together with the appropriate units relay. This would be one of the three relays, P'', 1P'', or 2P'' in Fig. 4. The tens relay and units relay thus selected having pulled up, their locking windings are grounded, and hence they are maintained energized through the locking common return as long as a subscriber keeps his receiver off the hook, being finally deprived of current when the subscriber hangs up, so that the relays are then restored.

100

105

110

I have thus shown, first, a single trunk group of primary selector relays and second, three such groups, or at least portions of three groups belonging to three several trunks and having the subscriber's lines connected to them in multiple. I will now point out how a calling line is permitted to select an idle trunk only, by working idle relays only. For this purpose it is necessary that I should refer briefly to Fig. 5. This figure shows a portion of a trunk circuit which is supposed to be the terminal point of attachment of the selector set shown in the preceding figures and in Fig. 7. This trunk is divided by the condensers C and C' so that the portion to the right of the condensers in the

115

120

125

130

figure can be used for sending direct current out through the switches without interfering with the incoming end. Across the incoming or answering end of the trunk is bridged 5 a pair of relays D and D' each with the main battery B between them. This battery is grounded as usual on its positive bus and when the primary selector set first puts a call on this trunk its sleeve relay D' will immediately pull up in series with the cut-off 10 relay of the calling line. The incoming end of the trunk, therefore, corresponds to the cord circuit of an ordinary manual system, the primary selector set performing the same 15 functions as the plug and jack; hence the battery supply for talking as well as for signaling over the calling line is supplied through the two relays D and D'. D' being the sleeve relay remains energized as long 20 as the primary selector set is on which is the same as saying as long as the answering plug is in the calling line jack. The relay D on the other hand responds to the subscriber's 25 acts, being energized by current coming over the subscriber's line and therefore controlled by his switch-hook. It will be observed in the switching end of the trunk there is a starting relay E which is normally deenergized but becomes energized when the talking 30 trunk is connected to an idle secondary set. I run the common wire 57 or 59 from the locking windings of all the primary selector relays of each trunk to a back contact on the starting relay E, this contact being 35 normally closed upon main battery B: This same wire is connected to a normally open contact on the relay D. These relays are all energized when the switching is done but they serve normally to keep current on the 40 locking wires so that when any set of relays pulls up it will be enabled to lock instantly even before the tip relay D of the trunk has pulled up. When this latter relay becomes energized it takes control of the locking 45 wire in every case and since the signaling relays are all locked up during a connection, the relay D alone controls the locking windings and releases the same to clear out when the calling subscriber hangs up 50 his telephone. Having thus shown that the locking windings are all maintained active it remains to point out how the actuating windings of the different selector relay sets are rendered active one at a time. This is 55 by means of the relays D' and D^x. In Fig. 5 it is assumed that the trunk shown is No. 1 and the lowermost trunk in Fig. 7 is No. 1. The instant a call comes in and is put on the first trunk, the sleeve relay D' is pulled up 60 and places battery on the relay D^x. This latter relay is normally deenergized and the actuating windings of the various tens and units relays belonging to its trunk are, therefore, normally closed onto ground through 65 the normally closed contacts of this relay

which is of the type shown in Figs. 9 and 10. The relay D^x upon being operated must open these circuits. Succeeding relays must leave them normally open, and when energized must close them. In other words, the relay 70 selector of the first or lowermost trunk is in condition to get current at once and hence will take the first call. As soon as this call is placed on the trunk the relay D' puts battery on a wire leading to a relay corresponding 75 to D^x of the next trunk. This latter relay becoming energized immediately closes battery onto the actuating winding of the relay primary selector set of its trunk which thereupon becomes sensitive and in condition to take the next call; and so on through 80 the succeeding trunks. I have shown only five contacts on each of the controlling relays for the sake of simplicity in illustration but it will be understood that there may be as 85 many as are required. Further details of the trunk arrangements will appear from the statement of operation.

Referring now to Fig. 5, in addition to the relays D, D' and E, the talking trunk contains the tip and sleeve relays S and S' for supplying talking current to the called subscriber and also to control the ringing relay Y. The relay S' becomes energized 90 when the called line is connected by being placed in series with the line cut-off relay. As soon as this happens the circuit of the ringing relay Y is closed through the interrupting machine Y'. The relay S becomes energized when the called party answers and 95 disconnects the ringing relay Y. Ground is placed on the starting wire 15 leading to the secondary set through the normally closed contacts e, e' of the relay E when the relay 100 D' becomes energized. The circuit of the 105 relay E is closed when the talking trunk is connected to the secondary set containing the selective buttons K. After this relay becomes energized it remains locked through the contacts e³ and e⁴ and under control of 110 the relay D'. The relay F closes the wires leading from the key set K onto their respective tens and units relays in Fig. 6. This relay also connects the trunk wires to the operator's telephone set through the 115 listening button K^x. This relay has two windings, namely, the actuating and locking windings, similar to those of the primary set. The locking winding is normally connected to battery through the contact h⁴ 120 and h⁵ of the relay H', while the actuating winding is connected to battery through the contacts f¹ and f² of the relay F'. This latter relay when energized closes the circuit of the signal lamp L notifying the operator 125 of a call. This relay is energized in series with the relay E when the relay F is operated and remains energized until the operator releases the starting button K^x. This starting button closes the circuit of the re- 130

lay H which in turn closes the circuit of the relay H' through the contacts h^2 and h^3 . After the relay H' has become energized, the locking circuit of the relay F is maintained through the contacts h and h' of the relay H. The operation of the relay H' places battery on the common springs of the key set K. The relay F which belongs to the talking trunk has its contacts connected to wires leading to the talking set K. There is a corresponding relay to every talking trunk, each containing multiple wires leading to this key set and also individual wires leading to connector relays such as shown in Fig. 6. For a 100 line exchange there would ordinarily be 10% of talking trunks which would mean that the exchange would be equipped with ten talking trunks identical with that shown in Fig. 5 and each containing a set of relays shown in Fig. 6.

The second selector set shown in the lower portion of Fig. 5 is adapted to be engaged by any one of the ten trunks. The circuits are so arranged that only one of these trunks can be connected to this secondary selector at a time, thus preventing interferences. The secondary selector is only connected to a trunk while the operator is taking the call and selecting the proper relays in the connector set by means of the key set K, after which the secondary set becomes idle and is in condition for another call. While the secondary set is engaged, any other trunk is prevented getting on it, on account of the relay F' being energized disconnecting the actuating windings of the relays F. The secondary set is disconnected from a trunk after the starting button K^x has been released in the following manner; the relay H becomes energized and in turn energizes the relay H' and after the operator removes her finger from the starting button, the relay H first falls back after which the relay H' falls back but during this interval the locking circuit of the relay F is opened and it, therefore, becomes deenergized and disconnects the wires leading to the key set from the wires leading to the relays in Fig. 6. Taking Figs. 5 and 6 together, the individual contact spring in key k' is connected to the relay T' when the relay F is energized by the following path: k' , 75, 76, T', to ground. The button k^2 is connected to the relay T² by a similar path: while the buttons k^3 , k^4 , and k^5 are connected respectively to the relays T³, T⁴, and T⁵ respectively. The buttons k^{11} , k^{12} , k^{13} , k^{14} , and k^{15} are connected respectively to the relays T¹¹, T¹², T¹³, T¹⁴, and T¹⁵ by similar paths. The relays T', T², T³, T⁴ and T⁵ are the tens relays and each contain the multiples of ten lines. In this present case for simplicity, I have only shown the terminals of five lines and instead of showing ten of these relays which would represent a 100 line exchange, I have

only shown five. The lower set of relays T¹¹, T¹², T¹³, T¹⁴ and T¹⁵, are the units relays and contain multiples leading to contacts in the tens relays. T¹¹ which corresponds to No. 1 digit has its contacts multiplied to the first pair of contacts in the relays T', T², etc., while the relay T¹², which corresponds to the second digit has its contacts multiplied to the second pair of contacts in the relays T', T², etc., and so on. Each one of the units relays contains a multiple of the talking trunk shown in Fig. 5, and if the relays T' and T¹¹ were the relays selected by the operator depressing the buttons k' and k^{11} , then the trunk would be connected to line 11 through the contacts t^{11} and t' . If the relays T¹¹ and T³ had been energized by their respective buttons being depressed, then the trunk would have been connected to line 31 through the contacts t^{11} and t^3 . From this combination of tens and units relays, it will be seen that the talking trunk can readily be connected to any one of 100 lines by the selection of the proper tens and units relays. These relays like the relays of the primary selector set are double wound and their locking circuit is controlled by the tip relay D in Fig. 5.

The buttons shown in the set K can be of any standard type such as used with selective ringing outfit in a great many exchanges. The only thing necessary is that when a button is depressed it must remain in a locked or indicating condition until another button is depressed whereupon it must assume its normal position.

Referring now to Fig. 8, I have shown a modification wherein the primary selector relays are replaced by mechanical switches. One of these switches is connected to the incoming end of each talking trunk and each switch contains the multiple of all the lines in the same manner that the tens relays contain the multiples of all the lines. A subscriber calling in energizes the line relay M through the normally closed contacts of the cut-off relay M'. The energizing of the relay M closes the circuit of all the stepping magnets in these switches through the common wire 603. As soon as the circuits of the stepping magnets are closed, the switches start to rotate and the first switch whose wiper z^2 makes connection with the contacts connected to the wire 602, will cease to rotate for the following reason: The relay D² connected to the wiper z^2 through the contacts d' and d^2 of the relay D has its circuit closed to battery through the contacts of the relay M. The energizing of this relay breaks the contacts d^8 and d^9 , disconnecting the stepping magnet D⁵. This relay besides breaking the circuit of the stepping magnet also connects battery to the relay D' which thereupon is connected in series with the line cut-off relay M'. The energizing of the re-

105

110

115

120

125

130

lay M' disconnects the line relay M thereby opening the starting circuit 603 leading to the stepping magnets of other switches. The line now being closed onto the trunk through 5 the wipers z' and z , the relay D becomes energized through the subscriber's telephone. This relay then disconnects the relay D^2 from the test wiper z^2 freeing it from all 10 connections and at the same time maintains the circuit of the relay D^2 through the contacts d and d' . The rest of the circuit and operation of the same is identical to that of Fig. 5, and need not be described. At the 15 end of the conversation and the breaking of the line circuit by the hanging up of the receiver at the calling station the relay D becomes deenergized and again connects the relay D^2 to the test wiper z^2 . The deenergizing of the relay D^2 removes battery from the 20 relay D' thereby opening the circuit of the relay M' , causing the line relay M to be again connected to the calling line.

I will now describe the operation of my system tracing a complete connection from 25 the calling to the called subscriber. For this purpose I will use Figs. 1, 2, 3, 4, 5, 6, and 7. Referring now to Fig. 1, when a subscriber at station A takes down his receiver, his line circuit 1-2 is closed, the relay M (and assuming that all connective apparatus is idle) 30 the relays 2N and 2P in Figs. 2 and 4 pull up their armatures, their return wires 53 and 56 being normally closed through the contacts of the relay D^x , in Fig. 5. Extension wires from the cut-off relay 2M' are 35 thus prolonged by way of contacts 500 and wires 210 to the trunk 230-231 in Fig. 4, and so on to the same wires in Fig. 5. Current immediately flows from the main battery B in Fig. 5 through the sleeve relay D' 40 and back through the sleeve side of the trunk to the cut-off relay 2M' to ground. The cut-off relay immediately pulls up connecting the subscriber's line onto the extensions and so on through the trunk whereupon the tip relay D of the trunk pulls up. 45 This closes battery to the locking wire 57, the same being temporarily maintained through the back contact of relay E . The relays 2N and 2P remain locked therefore subject to the control of the relay D which is controlled directly by the subscriber A. When the relay D' pulls up, it energizes the relay D^x which pulls up and cuts off all the 50 return wires of the selector relays 2N, 2P, etc., of its set. The trunk is thus disabled for any other calls. At the same time current passes through the wire 14^a to the armature of the relay of the next trunk corresponding to the relay D' , through a back contact thereof and so to the relay corresponding to D^x which pulls up and places battery on the actuating winding of the relays 1N, 1P, etc., of its set. Now taking it for 55 granted that the secondary set is idle at this

time, the circuit of the relay F would be closed as follows: ground, d^7 , d^6 , e , e' , 15, F , 45, f^2 , f' , 49, 20 and battery B. The relay F having its circuit thus closed connects the wires leading to various buttons in the key 70 set K to their respective relays in Fig. 6, at the same time it connects the trunk wires, 42 and 43 to the listening button K^x . The circuit of the relay E is at this time closed by the following path: ground, d^7 , d^6 , E , 17, 44, 75 F' , 49, 20 to battery B. This relay now remains energized and locked through the contacts e^4 , e^3 , 18, resistance coil I, 20 to battery B. After the relay E has thus locked itself, the relay F' remains energized by current 80 flowing through the relay E past the resistance coil I. I have used this resistance coil in this manner so as to prevent the shunting of the relay F' after the relay E becomes energized as enough current will flow through 85 the winding of the relay E to the relay F' to keep it energized. The operating of the relay F' closes the circuit of the lamp L which upon glowing notifies the operator of a call. She therefore depresses the listening button 90 K^x and asks for the number desired. Upon receiving the number, she proceeds to set up on the key set K the number desired by depressing the proper buttons. Suppose, for illustration, the number desired was 33. 95 The operator will, therefore, depress the button k^3 which is connected to and controls No. 3 tens relay in Fig. 6. She then depresses the third button k^{13} which controls No. 3 units relay in Fig. 6. 100

Referring now to Fig. 6, the circuit of the relay T^3 which is the third tens relay, has its actuating winding connected to the common wire 94 through the contacts of the button k^3 . The relay T^{13} , which is the third units 105 relay has its actuating winding connected to common wire 94 through wire 88 the contacts of the key k^{13} and the wire 95. The operator now having set up the number desired depresses the starting button K^x' which 110 closes the circuit of the relay H by the following path: battery B, 49, 47, contacts of the button K^x' , H to ground. The operating of this relay energizes the relay H' and at the same time maintains the circuit of the 115 locking windings on the relay F through the contacts h and h' . The operating of the relay H' closes the contact h^3 and h^{13} connecting battery to the common wire 94, and it, of course, follows that as the actuating windings of the relay T^3 and T^{13} are connected to 120 this wire through the contacts of their respective buttons, they will immediately become energized. The energizing of these two relays connects the trunk wires 42 and 43 to the line wires 1 and 2 respectively of the desired station, through the contacts t^3 and t^{13} . It will be noticed that the line 125 33 is the only one connected to the trunk wires 42 and 43, as the relay T^3 is the only tens re- 130

lay energized and the other nine lines having multiple contacts in it are free from all connections. The locking windings of the relays T^3 and T^{13} are connected to the common wire 13 leading to the contact d^2 in the relay D. This contact at the present time is connected to battery by way of the contacts d^8 , 14, 19, 20 to battery B. It will thus be seen that the calling subscriber has control 10 of all connections. After the operator has released the starting button K^x , the relay H becomes deenergized, opening the locking circuit of the relay F disconnecting the key set from the relays and also disconnecting the 15 operator's set preventing her from listening in on the connection. The relay F' is now disconnected, the lamp L extinguished and the secondary set ready for another call. The trunk now being connected to the desired line the relay S' becomes energized in 20 series with the cut-off relay in the line. The energizing of this relay closes the circuit of the ringing relay Y in series with the interrupting machine Y', the relay Y, being 25 energized intermittently, disconnects the answering or incoming end of the trunk from the calling end and places generator current on the latter, thus ringing the telephone of the called subscriber. The called subscriber, 30 answering his telephone closes the circuit of the relay S, disconnecting the ringing relay Y. At the end of the conversation the calling subscriber hanging up his receiver, energizes the relay D breaking the contacts 35 d^2 and d^8 , disconnecting the relays T^3 and T^{13} . The deenergizing of the relay D also takes battery off the locking wires 57, hence the two relays which are holding the calling line let go their armatures, become disconnected 40 from the line, the cut-off relay of the line loses current, connects on the line relay, and the sleeve relay D' of the trunk loses current, thereby cutting off the relay E, thus restoring 45 the entire apparatus to its normal or idle condition.

It will be noticed in connection with the ringing circuit as shown, if at the end of the conversation the called party hangs up his receiver before the calling party, that generator current will again flow over the called line. To prevent this a locking relay is added which will become energized and locked when the tip relay S is operated and thereby disconnect the ringing relay Y. 55 Such an arrangement is shown in Fig. 11, the locking relay being indicated at Y^2 . This locking relay is released when the calling party hangs up, deenergizing the relay D.

60 In Figs. 13, 14 and 15 are shown a relay primary selector set of exactly the same kind as that in Figs. 2, 3 and 4. No further description is needed for these figures therefore. In Fig. 12 I show the constantly act-

ing primary selector switch hereinbefore referred to and which I have lettered in its entirety Z^3 . This switch has a spindle z^3 , driven by any suitable motor, shown as a step by step ratchet device z^4 driven from the main battery B by means of a magnet z^{40} 65 and a commutator z^{41} . These specific details are for purposes of illustration only and form no part of my invention. The spindle z^3 carries three arms z^5 , z^6 and z^7 , which rotate over the circular series of contacts z^8 , z^9 and z^{10} . The contacts z^8 in a full size 70 switch are 100 in number, each connected through a back contact on the cut-off relay to one side of a line of the group associated with the primary selector group to which the switch Z^3 belongs. The contacts z^9 are connected in order to the tens relays of the same set, and the contacts z^{10} are connected in serial order to the units relays. In the switches actually shown in Fig. 12, there are 75 only thirty contacts in each of the groups z^8 and z^{10} , or three for each contact z^9 . This is because there are only three tens relays, or provisions for thirty lines in the primary selector set illustrated in Figs. 2, 3, 4, 13, 14 and 15. In a full sized switch there would 80 of course be ten of the contacts z^8 and z^{10} for each of the contacts z^9 . The operation of this switch is as follows: When any one of the lines terminating at the left of Fig. 13 85 is calling, battery current flows out over the sleeve side of the line to the substation and back over the tip side of line to the line contact z^8 . As the spindle z^3 rotates, carrying 90 the arms with it, the arm z^5 comes upon the calling contact z^8 , and current immediately flows to the relay M^x , which pulls up and for that instant puts current on the arms z^7 and z^6 . Now, when the arms z^5 is resting on 95 a particular line contact, the arm z^6 rests upon the tens relay contact controlling the group of ten in which that line falls, and the arm z^7 rests upon the contact of the unit relay corresponding to the unit digit of the line. In other words, for each long contact 100 z^9 passed over by the arm z^6 , the arm z^7 passes over ten (in my limited illustration three). Hence the necessary tens and units 105 relays pull up to connect the calling line with the trunk in Fig. 16, the control of which thereafter is maintained by the subscriber in identically the same way as in 110 Fig. 5 already described.

It will be observed that by using the switch Z^3 and the relay M^x for each trunk, 115 all the line relays are done away with, and only one call can come in at a time on any trunk.

Having thus described my invention what I claim and desire to secure by Letters Pat- 125 ent is:

1. In a telephone exchange system, a central office, a plurality of subscribers' lines to

- be interconnected, and central office switching means for interconnecting them, comprising a trunk, means to connect calling lines with the trunk, a plurality of relays intermediate the trunk and the lines and containing each terminal contacts of a plurality of lines, and control means for said relays comprising an operator's key set arranged to selectively control the circuits of the relays, whereby called lines may be connected with the trunk at the will of the operator. 5
2. In a telephone exchange system, a central office, a plurality of line circuits to be interconnected, and central office means for interconnecting the same comprising a plurality of relays containing line contacts and an associated trunk circuit together with means at the central office common to all of 10 said relays and trunk and controlled by the central office operator for energizing the relays selectively.
3. In a telephone exchange system, a plurality of line circuits, and means to interconnect the same comprising a trunk circuit and a plurality of relays each having contacts of a plurality of lines connected to said line circuits, and switching devices having identifying contacts connected with the lines 15 directly controlling the relays.
4. In a telephone exchange system, a plurality of line circuits, a plurality of relays for interconnecting the said circuits for conversational purposes, and unitary switches 20 with traveling contacts controlling commonly a plurality of circuits separate from the talking circuits and from subscriber's apparatus for directing and actuating the relays.
5. In a telephone exchange system, a plurality of line circuits, and connective means therefor comprising relays exclusively for the talking circuits and unitary switches 25 with traveling contacts controlling commonly to a plurality of the relays, the said switches being separate from and independent of talking circuits and subscriber's apparatus.
6. In a telephone exchange system, a plurality of line circuits, a plurality of trunk circuits, means to connect calling lines with said trunk circuits, and a group of selective relays associated with each trunk, together with means for supplying energizing current to the same individually and selectively so as to select any desired line from the trunk, and connect the trunk thereto through the relay contacts, the said latter means being separate from and independent of talking circuits and substation apparatus. 50
7. In a telephone exchange system, a plurality of line circuits, and means to interconnect them comprising relays each containing contacts of a plurality of lines and
- adapted to complete the talking circuits, and 65 unitary selective switching devices each with a plurality of fixed and traveling contacts for controlling the relays.
8. In a telephone exchange system, means for interconnecting line circuits, comprising 70 main and auxiliary selective unitary groups of relays, link circuits inter-connecting the groups, and separate controlling means for selecting and actuating predetermined relays in each group to inter-connect desired 75 lines through successive links.
9. In a telephone exchange system, a plurality of circuits to be selected and connected, a trunk circuit, and selecting means associated therewith comprising a double set 80 of relays, the relays of one set controlling each a definite group of line contacts, and the relays of the other set controlling each a definite unit contact in all the groups of the other set, together with a switch common to 85 a plurality of lines and controlling the actuation of said relays in accordance with the identity of the line calling.
10. In a telephone system, a series of line circuits, a set of relays each containing terminals of a plurality of said circuits, a cable or set of trunk wires connected in multiple to corresponding terminals in all of said relays, a supplementary set of relays, each 90 supplementary relay controlling a branch 95 from one only of the cable wires, controlling circuits for the several relays, a source of current, switching means for determining the supply of current to said circuits, and means for bringing said switching means 100 into co-operative relation with the circuits in initiating a connection and for disabling the same thereafter.
11. In a telephone system, a series of line circuits, a set of relays each containing terminals of a plurality of said circuits, a cable or set of trunk wires connected in multiple to corresponding terminals in all of said relays, a supplementary set of relays, each 105 supplementary relay controlling a branch 110 from one only of the cable wires, controlling circuits for the several relays, a source of current, switching means controlled by an operator for determining the supply of current from said source to said circuits, and 115 means for connecting and disconnect said switching means.
12. In a telephone system, a series of line circuits, a set of relays each containing terminals of a plurality of said circuits, a cable 120 or set of trunk wires connected in multiple to corresponding terminals in all of said relays, a supplementary set of relays, each supplementary relay controlling a branch from one only of the cable wires, controlling 125 circuits and a source of current for said relays, operators' keys for selectively determining the supply of current from said

source to said controlling circuits, and means for connecting and disconnecting said keys.

13. In a telephone exchange system, a plurality of lines to be interconnected, and a trunking system for interconnecting them comprising a plurality of connective links adapted to extend the connection, primary selector switching devices arranged to connect the links to calling lines, and digital relay selective switching devices forming the connector terminals of the links, together with central station means common to all of said digital relay switching means and arranged to selectively operate the relays of the switching means of each link.

14. In a telephone exchange system in combination, a plurality of lines, a plurality of connective links for interconnecting them provided at one end with terminal means to connect with calling lines and at the other each with a digital relay selective switching means arranged to connect through the energization of the relays with called lines, together with a central station control device for said switching means common to switching means of all the links.

15. In a telephone exchange system, a

plurality of line circuits, a plurality of trunks less in number than the line circuits, means to connect an idle trunk with a calling line, a group of selective connecting relays associated with each trunk and adapted to connect the same with any one of a number of other circuits, and manually operated means for controlling said relays.

16. In a telephone exchange system, subscribers' lines divided into groups, connector links for connecting with wanted lines of the groups, means associated with each of said links for selecting a group of terminals containing the line of the called subscriber, and separate means associated with each connector link for selecting the number in the group corresponding to the line of the called subscriber and effecting the final connection, and a sending device to actuate said line selective means.

In testimony whereof I affix my signature in presence of two witnesses,

EDWARD E. CLEMENT.

Witnesses:

E. EDMONSTON, Jr.,
G. L. BABCOCK.
